FIG. 4

INVENTOR
E. LANGERMAN

BY *Wright & Co.*
ATTYS.

UNITED STATES PATENT OFFICE.

EARL LANGERMAN, OF SAN FRANCISCO, CALIFORNIA.

ILLUMINATED VANITY BOX.

Application filed May 23, 1922. Serial No. 563,178.

To all whom it may concern:

Be it known that I, EARL LANGERMAN, a citizen of the United States, residing at San Francisco, in the county of San Francisco and State of California, have invented new and useful Improvements in Illuminated Vanity Boxes, of which the following is a specification.

This invention relates to improvements in vanity boxes, toilet cases, ladies' purses and the like and has particular reference to a novel and inexpensive means for illuminating said boxes or like containers and for making possible an effective use of the mirror contained in the box, in theaters and other places where the light is insufficient to permit of the proper use of the mirror.

An object of the invention is to provide a simply constructed means of illumination for vanity boxes, which may be readily incorporated in the boxes without necessitating materially changing the construction thereof.

An object is to provide in an illuminated vanity box of the character described a novel and easily accessible circuit closer.

The invention further includes simple and efficacious apparatus of the character described comprising numerous details of construction and combinations which will be hereinafter more fully described.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawing:

Fig. 1 represents a perspective view of a vanity box constructed in accordance with my invention.

Fig. 2 represents a fragmentary sectional view illustrating the manner of mounting the battery and circuit closer.

Fig. 3 is a cross sectional view through the box.

Fig. 4 is a longitudinal sectional view showing the circuit closer in detail.

Referring to the embodiment of the in-

vention illustrated in the accompanying drawing, 1 designates a box or case of the type commonly used as vanity boxes, having a hinged lid or cover 2. In this box or case are contained numerous toilet articles such as usually constitute the contents of vanity cases or boxes, and in the lid 2 is mounted a mirror 3. The mirror 3 is constructed so that substantially the entire area of the under side of the lid is taken up by the mirror and the mirror will be available for use when the lid is raised as shown in Fig. 1.

I preferably mount an electric light socket 4 in the lid 2 adjacent the outer edge of the lid on the inner side thereof and employ a small incandescent lamp 5 which is mounted in the socket. The upper edge of the mirror is cut away or notched as at 6, so that the notch will conform closely to the socket and permit of the forward projection of the socket and lamp in a position over the mirror. By provision of the notch, a mirror fitting substantially the entire inner surface of the box may be used.

Mounted adjacent one end wall 7 of the box is a battery holder generally designated 8. This holder is in the form of a flap made up of hingedly connected sections or strips 9, 10, 11 and 12. Each section may comprise a strip of cardboard encased in a cloth or fabric covering. The strip 9 is comparatively narrow and glued or otherwise secured to the bottom 13 of the box at a point spaced from the wall 7. The strip 10 extends upwardly from the strip 9 and the strip 11 extends horizontally towards the wall 7. The strip 12 extends upwardly parallel to the wall 7 and is adapted to lie against said wall. By means of a snap fastener 14, the strip 12 is removably fastened to the wall. A small dry battery 15 is held in place between the bottom wall 13, end wall 7 and holder 8.

Fixed to the end wall 7 are contact members 16 and 17 adapted to engage the usual contact points at the ends of the battery and at the same time hold the battery in place. Leading from the contact point members 16 and 17, are conductors 18 and 19. The conductor 18 extends behind the lining 20 on the inner side of the wall 7 of the box to and is connected with a leaf spring contact strip 21. The strip 21 is secured by a fastening 22 to the wall 7 and at its outer end is normally spaced from a contact point 23 provided in the wall 7. To prevent the lin-

ing 20, which is usually stretched comparatively tight, from engaging the contact member 21 and moving it into engagement with the contact 23, I provide a guard member 24 which is of greater thickness than the contact member 21 and is secured in any suitable manner to the wall 7. A longitudinal slot 25 is provided in the member 24 and receives the contact member 21 therein, 10 in such manner that said member 21 is spaced from the lining 20 but may be forced inwardly so as to engage the contact 23 by pressing on the lining at a point over the slot. The contact means herein described is 15 located preferably, near the rear side of the box so that in holding the lid open, with the thumb extending into the box, ready access is had to the contact means or circuit closer. The other conductor 19 extends behind the 20 lining 20 on the rear wall of the box to a coiled spring 27. A conductor 28 leads from the contact member 23 behind the lining 20 to a similar coiled spring 29. The springs 27 and 29 are secured adjacent opposite ends 25 to the lid and box respectively in such manner that they will be twisted when the lid is raised.

Extending from the springs are conductors 30 and 31 which lead to the lamp 30 socket, said conductors being concealed behind the mirror. By the use of these springs the lid may be moved into and out of closed position without in anyway affecting the electrical connection between 35 the lid and the box, since the springs will readily give and expand upon movement of the lid. The springs are concealed in the lining 20 which extends from the rear wall of the box into the lid to a point behind the 40 mirror.

By having the battery holder secured at its lower end to the bottom wall all possibility of pins or other small articles collecting under same will be eliminated. The 45 battery may be easily removed by unfastening the snap fastener and moving the holder so that access to the battery is had. The member 8 in being made of hinged sections provides for this movement whereby ready 50 access to the battery may be had.

With the device of my invention it will be seen that the battery which is the largest part of the electrical apparatus will be mounted so as to take up little or no room 55 and such that it may be readily taken out for replacement of a new battery as desired.

The contact mechanism of my invention, that is the switch, is concealed and the wires are likewise concealed so that in its 60 entirety the mechanism of the invention is hardly perceptible when opening the case,

except for the electric light which projects at the upper or outer edge of the mirror. When it is desired to illuminate the box and mirror, the operator grasps the box as 65 shown in Fig. 1 and by pressing inwardly on the lining will move the contact 21 to engage with the contact 23 and thereby close the circuit for the lamp.

One of the main features of the invention 70 is to provide for illumination as desired with mechanism which may be readily incorporated in purses, vanity boxes and the like, of various construction, the said mechanism being inconspicuous, inexpensive and 75 not liable to getting out of order or becoming deranged.

I claim:

1. The combination with a vanity box having a hinged lid, of a mirror supported 80 by the lid, an electric lamp carried by the lid and projecting outwardly from the mirror, a source of electrical energy mounted in the box, conductors leading from said source to the electric lamp, a circuit closer mounted in one wall of the box and accessible from a point interiorly of the box, said circuit closer being responsive to a pressure from the thumb or fingers of a hand and a lining in the box extending over and concealing the circuit.

2. The combination with a vanity box having a hinged lid, of a mirror supported by the lid, an electric lamp carried by the lid and projecting outwardly from the mirror, a source of electrical energy mounted in the box, conductors leading from said source to the electric lamp, a circuit closer mounted in one wall of the box and accessible from a point interiorly of the box, 90 said circuit closer being responsive to a pressure from the thumb or fingers of a hand and a lining in the box extending over and concealing the circuit, said mirror being notched and receiving the electric lamp 95 in the notch thereof.

3. A vanity box of the character described comprising a box member, a lid hinged to the box, a mirror supported by the lid an electric light carried by the lid and extending outwardly from the mirror, coiled springs attached to the lid and box, conductors leading from the springs to the electric light, a source of electrical energy, means for concealing the source of electrical energy within the box, conductors leading from the source of electrical energy to the springs and a circuit closer within the box and associated with said last named conductors.

EARL LANGERMAN.
